CONCEALABLE DESK PAD

Martin E. Trollen, St. Paul, Minn., assignor to
 Brown & Bigelow, St. Paul, Minn., a corpora-
 tion of Minnesota

Application July 21, 1939, Serial No. 285,682

5 Claims. (Cl. 281—44)

My invention relates to an improvement in desk memorandum pad wherein it is desired to provide a pad which is normally concealed from view but which is readily accessible when it is desired for use.

Desk memorandum pads of numerous types have been previously constructed. Certain of these pads have been provided with covers which conceal the material written upon the pad from view. These former constructions, however, have a definite disadvantage. The pads are made to support a varying number of sheets, and as the pad is used, fewer sheets remain thereupon. Therefore, a cover of the ordinary type used upon the pad will not fit down properly upon the sheets regardless of the thickness of the pad. Thus the cover oftentimes would detract from the appearance of the pad rather than improve the appearance.

It is a feature of my invention to provide a desk memorandum pad mounted upon a rigid base and to provide a cover hingedly secured to the base capable of concealing the pad regardless of whether one sheet or a maximum number of sheets remains on the pad. The construction thus provided remains neat regardless of the degree of depletion of the pad, and the cover fits in place the same way when the pad is new as when most of the sheets are used.

It is a feature of my invention to provide a construction in which the pad is concealed within a box-like container. A cover is provided hingedly secured to the base and springs are interposed between the base and cover to normally urge the cover into open position. A latch holds the cover in closed position, and by merely releasing this latch, the cover will move under spring tension into open position.

It is a feature of my invention to provide dampening springs in addition to the springs for urging the cover into open position. These dampening springs tend to urge the cover toward a midway open position, but are not as strong as the spring urging the cover into full open position. These springs assist the opening action of the cover when more force is required to pivot the cover, but act to dampen this opening movement so that as the cover approaches fully open position, these springs tend to slow the pivotal motion of the cover. Thus these auxiliary springs not only aid the other springs when the greatest spring action is necessary, but also prevent the cover from jerking into fully open position.

These and other objects and novel features of

my invention will be more clearly and fully set forth in the following specification and claims.

In the drawings forming a part of my specification:

- 5 Figure 1 is a perspective view of my desk pad in closed position.
 Figure 2 is a perspective view of the same in fully opened position.
 Figure 3 is a longitudinal cross-sectional view, 10 longitudinally through my desk memorandum pad on a plane through one of the paper retaining studs.
 Figure 4 is a rear end view of my desk memorandum pad in closed position.
 15 Figure 5 is a cross-sectional view centrally and longitudinally through an end of my desk memorandum pad in partially opened position.
 Figure 6 is a detail view of the hinged edges of my desk memorandum pad in open position.
 20 The desk memorandum pad A includes a container portion having a top 10 and a base or bottom portion 11 and having mounted upon the base 11 a pad of sheets B. The base 11 includes a rectangular body member 12 having upturned side and end flanges 13. A stiffening or reinforcing member 14 overlies the body portion 12 on the base, and a lining sheet 15 extends over the reinforcing member 14 and body portion 12. A covering sheet 16 overlies the outer surface of the upstanding flanges 13 and this marginal covering sheet folds over the marginal edge of the base to provide a flange 17 along the edge of the bottom of the body portion 12. A bottom covering sheet 19 is secured to the lower surface of the body portion 12 in overlapping relation with the flange 17 to entirely conceal the body portion 12. A reinforcing channel-shaped edge 20 completely encloses the upstanding flanged edges 13.

Anchored between the anchoring member 14 and the body portion 12 I provide a head 21 of a stud 22 which projects upwardly through a reinforcing member 14 and the lining sheet 15. A pair of these studs 22 projects upwardly from the base near one end thereof in spaced relation. These studs are designed to extend through perforations in the pad of sheets B and to accommodate internally threaded sleeves 23 having a head 24 at their upper extremities. The head 24 as illustrated in Figure 2 engages the top sheet of the pad B to hold the various sheets in place.

The cover 10 includes a top body portion 25 having marginally downwardly extending flanged edges 26 about the periphery of the same. A lining sheet 27 is adhered to the under surface

of the body 25 and to the inner surface of each of the flanges 26. An outer covering sheet 29 is adhered over the outer surface of the body portion 24 and the flanged edges 26. A channel 30 preferably formed of metal or other relatively stiff material encloses the marginal edge of the flanges 26 together with the respective covering and lining sheets 29 and 27 respectively.

A hinge 31 connects one end of the base 11 to a corresponding edge of the top 10. The opening movement of the cover with respect to the base is limited by pairs of rods 32 and 33. The rods 32 are secured to the channel 20 on the upstanding flange 13 of the base 12, while the bars 33 are secured to the channel 30 on the peripheral flanges 26 of the cover 10. When in open position as indicated in Figure 6 of the drawings, the bars 33 are moved into engagement with the bars 32, limiting the opening movement of the cover 10 with respect to the base 11.

In order to urge the cover into open position, I provide a spring 34 which surrounds the pivot shaft of the hinge 31. One end 35 of the spring 34 is anchored to the base 11, while the other end 36 is secured to the cover 10, this spring 34 tending to pull the cover 10 into the open position illustrated in Figures 2 and 6 of the drawings as soon as the latching means holding the pad closed is released.

The latch comprises a keeper 37 which is secured to the channel 30 of the top 10 as best illustrated in Figure 5 of the drawings, and a pivotal hook latch 39 which is secured to the base 11. A strap 40 bent into a loop shape extends about a wire spring 41 positioned within the channel 20. This spring 41 is merely an elongated spring wire soldered or otherwise affixed to the inner surface of the channel and tending to pull the strap 40 inwardly. In disengaging the hook latch 39, it is necessary to pivot the hook portion 42 of the latch out of engagement with the keeper 37. This is done by merely pressing down on the handle portion 43 of the latch which flexes the spring 41 to some extent and permits the opening of the cover 10. When the downward force is removed from the handle portion 43, the spring 41 moves the hook latch 39 into its normal position. The keeper 37 is so shaped that it will automatically engage the hook portion 42 of the latch as the cover 10 is closed. A pair of springs 44 connect the top 10 with the base 11 and assist in the opening of the cover and at the same time retard the opening of the cover moving into fully open position. The springs 44 are provided with a loop end 45 which is pivoted to one side of the channel 20 on the base 11 and a loop portion 46 which is pivoted to the inner surface of the channel 30 on the top 10. A spring coil 47 is provided intermediate the ends of each spring. This spring coil is so constructed that the normal expansion of the spring is between the closed position of the cover 10 and the open position thereof. In other words, if the spring 34 were eliminated, the springs 44 would open the cover or top 10 to a point midway between closed position and open position. The springs 44, however, are not as powerful as the spring 34, and therefore the spring 34 acts to open the cover or top into fully open position.

It will be seen that when the cover is in closed position, the coil 47 will be compressed beyond its normal point and the spring 44 will provide a tendency to open the cover 10. Thus the springs

44 supplement the action of the spring 34 as the cover starts to open. As the cover 10 pivots beyond a central position, however, the springs 44 open beyond their normal position and act to retard the opening of the cover. The greater the cover 10 is open, the more tension is placed on the springs 44. Thus as the spring 34 moves the cover 10 into open position, the opening movement is retarded to such an extent that the cover 10 will move relatively slowly into fully open position and therefore no jar will accompany the limiting of the pivotal movement.

In accordance with the patent statutes, I have described the principles of construction of my desk memorandum pad; and while I have endeavored to set forth the best embodiment thereof, I desire to have it understood that this is only illustrative of a means of carrying out my invention, and that obvious changes may be made 15 within the scope of the following claims without departing from the spirit of my invention.

I claim:

1. A desk pad device comprising a base, a cover hinged thereto movable between open and closed positions, spring means urging said cover into open position, a latch for holding said cover closed, a second spring means weaker than said first named spring means retarding movement of said cover into either open or closed position, and 20 a pad of paper on said base.

2. A desk pad device comprising a base, a heavy flat reinforcing sheet substantially the area of said base, a pair of spaced studs projecting through said reinforcing sheet and upwardly 25 from said base, a cover pivoted to said base, a pad of paper on said base having perforations therethrough through which said studs extend, and internally threaded sleeves adjustably secured on said studs having heads thereon to bear 30 upon the top of said pad.

3. A desk pad device comprising a base, a pad mounted thereon, a cover hinged to said base and movable between open and closed positions, a spring tending to open said cover, means to limit 35 pivotal opening movement, spring means weaker than said first named spring tending to hold said cover in a semi-open position and retarding movement toward both open and closed positions, and means normally holding said cover in closed 40 position.

4. A desk pad device comprising a base, a pad mounted thereon, a cover hinged to said base movable between closed and open positions, a spring urging said cover into open position, a pair of opposed springs connecting said cover and 45 said base, said pair of springs being relatively weaker than said first named spring, said pair of springs tending to urge said cover from both open and closed positions toward a partially open position and retarding the movement of said cover into either extreme position, and releasable 50 means to hold said cover in closed position.

5. In combination, a base, a closure pivotally secured to said base to move between two extreme positions, a spring tending to pivot said closure into one of said extreme positions, and a second spring relatively weaker than the first mentioned spring, tending to urge said closure from both of said extreme positions toward an intermediate position between said extreme positions.

MARTIN E. TROLLEN.
